(57) **CLAIM**

The ornamental design for an underwater cleaning robot, as shown and described.

DESCRIPTION

FIG. 1 is a top, front and left side perspective view of an underwater cleaning robot showing our new design; FIG. 2 is a bottom, rear and left side perspective view thereof;

FIG. 3 is a front elevation view thereof, the rear elevation view being a mirror image of the front elevation view; FIG. 4 is a side elevation view thereof, the view from the other side being a mirror image of the side elevation view; FIG. 5 is a top plan view thereof; and, FIG. 6 is a bottom plan view thereof.

The broken lines in the drawings illustrate portions of the underwater cleaning robot that form no part of the claimed design.
